UNITED STATES PATENT OFFICE

97,558

DESIGN FOR A SCRAPER

Earl B. Maloon, Milwaukee, Wis., assignor to The Heil Co., Milwaukee, Wis., a corporation of Wisconsin

Application September 26, 1935, Serial No. 58,719

Term of patent 14 years

To all whom it may concern:

Be it known that I, Earl B. Maloon, a citizen of the United States, residing at Milwaukee, in the county of Milwaukee and State of Wisconsin, have invented a new, original, and ornamental Design for a Scraper, of which the following is a specification, reference being had to the accompanying drawings forming part thereof.

In the drawings:

Fig. 1 is a full top view of the scraper with a portion of the draw bar broken away for convenience of illustration;

Fig. 2 is a side perspective view of the scraper with the draw bar likewise broken away;

Fig. 3 is a front perspective view of the scraper; and

Fig. 4 is a rear perspective view of the scraper, showing my new design.

I claim:

The ornamental design for a scraper, substantially as shown.

EARL B. MALOON
